[57] CLAIM

The ornamental design for a paint brush and roller cleaning tool, as shown and described.

DESCRIPTION

FIG. 1 is a top plan view of a paint brush and roller cleaning tool showing my new design;

FIG. 2 is a left side view thereof;

FIG. 3 is a right side view thereof;

FIG. 4 is a top end view thereof; and,

FIG. 5 is a bottom end view thereof.

The broken line showing of the handle is for illustrative purposes only and forms no part of the claimed design.
